[57] CLAIM

The ornamental design for a combined portable breathing unit and holster therefor, as shown and described.

DESCRIPTION

FIG. 1 is a top, rear and left side perspective view of a portable breathing unit showing my new design;
FIG. 2 is a top, front and right side perspective view thereof;

FIG. 3 is a left side elevational view thereof;
FIG. 4 is a top plan view thereof;
FIG. 5 is a rear elevational view thereof;
FIG. 6 is a top, rear and left side perspective view of a combined portable breathing unit and holster therefor;
FIG. 7 is a top, front and right side perspective view of FIG. 6;
FIG. 8 is a left side elevational view of FIG. 6;
FIG. 9 is a top plan view of FIG. 6; and
FIG. 10 is a rear elevational view of FIG. 6.
